CLAIM

The ornamental design of a vehicle pillar unit without opening, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a front perspective view of a right vehicle pillar unit without opening showing my new design, the left being a mirror image thereof;

FIG. 2 is a top perspective view thereof;

FIG. 3 is a front perspective view of a left pillar unit thereof; and,

FIG. 4 is a top perspective view thereof.
